FLOTATION APPARATUS.

Application filed July 5, 1924. Serial No. 724,250.

Our invention is an improved apparatus for the flotation concentration of ores, but has utility for other processes wherein it is necessary to agitate or aerate, or both agitate and aerate a body of liquid or of mixed liquid and solids. In the practice of the flotation process by the mechanical agitation method, it is generally, in fact almost invariably, desirable to subject the ore pulp to agitation in a considerable number of separate agitation cells. This involves the necessity of providing some means of conveying the pulp from cell to cell and maintaining it at the proper level in each cell. Where the conformation of the land admits it is often convenient to effect this purpose by placing the cells successively at a lower level and initially supplying the pulp to the uppermost cell. It frequently happens however, that it is necessary or advantageous to build all of the cells upon the same level. In some flotation plants individual motors are provided for propelling the agitation mechanism of each cell, the agitator shafts in cells of this type generally being vertical. Our invention is designed as an improvement in the type of machines wherein the agitators are mounted upon a horizontal shaft. The length of a single cell provided with such a horizontal shaft or the number of such cells which can be placed in series and operated by a single shaft is limited by the practical length of shaft that can be used without resulting in injurious whipping and vibration. In our improved apparatus, we provide a plurality of bearings for the horizontal shaft, these bearings being placed in spaces from which the pulp is excluded, such spaces being conveniently provided in the form of the apparatus illustrated by a sufficient separation of the successive cells to provide spaces therebetween to accommodate the necessary bearings, and we provide for the moving of the pulp from cell to cell by mounting elevators upon the shaft, whereby the pulp is elevated sufficiently to impart the necessary flow by gravity. By means of this arrangement we are enabled to place all of the cells on one level and to provide the agitator and elevator shaft with as many bearings as necessary to insure practically vibrationless operation. A series of cells so constructed can be extended to

practically any desired length on one level depending only upon the extent to which it is practical to carry the diameter of the shaft in order to properly transmit the torque.

In the drawings:

Figure 1 is a plan view, with certain details omitted, of three flotation cells embodying my invention.

Figure 2 is a plan view upon an enlarged scale of one of the cells shown in Figure 1.

Figure 3 is a transverse sectional view upon the line 3—3 of Figure 2.

Figure 4 is a transverse sectional view upon the line 4—4 of Figure 2.

Figure 5 is a longitudinal sectional view of one of the conical deflectors fixed to the shaft at the points where it passes through the walls of the cells.

Figure 6 is a transverse section taken on line 6—6 of Figure 2.

Figure 7 is a transverse section on line 7—7 of Figure 2.

Figure 8 is a transverse section on line 8—8 of Figure 1.

Figures 9 and 10 are respectively cross sectional views on lines 9—9 and 10—10 of Figure 2.

As illustrated in Figure 1, the pulp is initially delivered by any suitable means to the cell 1, shown at the right, this being the head of the machine. As shown herein the three cells 1, 2 and 3, are similar except in the fact that cell 1 is not provided with any elevator mechanism, the pulp being initially delivered to that cell from some outside source. Manifestly the initial cell may also be provided with an elevator, if desired. At the head end of the second and third cells, we show elevator chambers 4—4 and the agitator or impeller chambers G. In the form shown each cell is divided into two compartments, g—g, by means of a partition 5. In practice, the number of partitions may vary or be entirely dispensed with but in most instances one or more such partitions are advantageous in order to get better control of the differing grades of concentrates.

Referring to Figure 1, it will be observed that we have provided bearings for the main shaft 6, at 7 and 8, these two bearings being located at the head end of the machine;

at 9 and 10, between the cells 1 and 2, and 2 and 3 respectively; and at 11, the tail end of the machine. This shaft may be operated from any suitable source of power as 5 through a belt applied to the pulley 12.

Each cell is of substantially rectangular form and comprises a vertical back wall 13, and vertical end walls 14 and 15. As indicated in Figure 6, the front wall 16, opposite the agitator rotor extends upwardly to a point somewhat below the level of the axis of the shaft and there carries an inclined apron 17 provided at its upper edge with a vertical lip 18 over which the concentrate 10 froth flows into the launder 19. The height of front wall 16, the presence or absence, and the size of members 17 and 18 are preferably controllable at will to suit the requirements of the pulp under treatment. 15

20 By the use of members 17 and 18 as shown in Figure 6 we get the effect of a spitz-box with a constricted lip the amount of constriction depending on the length of member 17.

25 The transverse partition 5, as indicated in Figure 4, is provided with an opening 20, extending across and immediately adjacent the bottom of the cell. Mounted upon the shaft 6, are elevator and agitator rotors, 30 said agitator rotors being provided in all of the cells and elevator rotors in such of the cells as desired. As shown herein elevator rotors are provided in each of the cells after the first. The agitator rotors are preferably mounted in each agitator compartment, such rotor being shown in transverse section in Figure 6 and consisting of a pair of spaced pulleys 21, 21 or the like upon the rims of which are affixed a series of longitudinal strips 22, separated by intervening spaces 23. The elevator compartment 4 is relatively short and contains an elevator rotor of construction similar to that of the agitator rotors, but consisting of but one 35 pulley member, so it is of less length longitudinally of the shaft. The construction of the elevator rotor is shown in Figure 7 and comprises the pulley 24 upon the periphery of which there are mounted a series of longitudinally extending angle irons 25, separated by intervening spaces 26.

Extending over the entire top of each cell, (see Fig. 6) is a hood 27, at the front of which is a depending vertical wall 28, which 55 terminates below the level of the shaft 6, and of the over flow lip 18. A vertical baffle 29, has its upper part between the depending wall 28 and the periphery of the agitator rotor. The agitator rotor revolves in the direction indicated by the arrow 32, and throws the pulp upward and forward as indicated by the arrows 30 and at the front of the cell the pulp passes through the space 31 into the spitz-box K as indicated by the 60 arrow at that point. The lower edge of the

baffle 29 is spaced above the floor of the cell as indicated at 33, and preferably an inclined floor 34 extends from the front wall 16 to the horizontal floor of the cell to assist in directing the flow of pulp through the space 70 33, in the direction indicated by the arrow placed at that point.

The baffle 29 in connection with the front wall 16 and floor board 34, forms a spitz-box 75 at the front of the cell, the overflow of froth over the lip 18 being received in the launder 19 and discharged through the duct 35.

The distribution of parts in the elevator chambers 4, is clearly shown in Figure 7. In the front of the elevator chamber, the 80 front wall 16 extends to the top of the machine instead of terminating at a discharge apron 17, as described in connection with the flotation chambers. At some distance inside of the front wall 16, the elevator 85 chamber is provided with a wall 36, which extends upwardly from the floor parallel to the shaft 6 and is provided at its upper edge with an apron 37 which inclines toward the elevator rotor and terminates in immediate 90 proximity thereto.

Pulp delivered to the bottom of the elevator chamber is thrown upward by the revolution of the elevator rotor and is thrown forwardly into the space between 95 walls 36 and 16 as indicated by the arrows 60.

The pulp consisting of water carrying the usual proportion of powdered ore in suspension is delivered to the head end A of the 100 apparatus. Cell 1, as herein shown, may be employed primarily as a mixing cell for the dissemination of the flotation agents throughout the body of pulp and for giving it a preliminary agitation and aeration. 105 No elevator mechanism is ordinarily necessary in such a mixing cell, for the reason that the pulp is usually delivered to that cell from a suitably arranged outside source. Cell 1 is constructed substantially the same 110 as the agitator cells differing only in minor details, as will subsequently appear. Its construction is shown in Figure 8 which is a sectional view through cell 1 used as a mixing cell. Ordinarily, by reason of the 115 adjustment of the pulp level in the first cell and the fact that the pulp does not become thoroughly aerated at this early state of its treatment, a comparatively small amount of froth, sometimes practically none, overflows the lip 18^a of cell 1, but provision is made for receiving such froth as may overflow, cell 1 being fitted with a launder 19^a like those on the following cells. The pulp supplied thereto flows to the bottom, where it 120 is caught by the peripheral bars 22^a of the agitator rotor and thrown upward and forward through the space 31^a into the spitz-box K formed between the front wall 16^a and the depending wall 28^a and baffle 29^a.

125 130

Some of the pulp is carried completely around the periphery of the rotor, the proportion between the amount carried around the rotor and that flowing to the spitz-box 5 through space 31^a depending on the speed of rotation of the rotor and the relation of the parts of the machine.

In case the level of the pulp and the amount of froth formed in the mixing cell 10 are such as to cause an overflow of froth over the lip 18^a, the froth concentrate is collected in the launder 19^a. The bulk of the pulp, however, returns from the spitz-box K to the main body of the mixing cell through 15 the opening 33^a whence it is again thrown upward, thus repeatedly going through the cycle above described as it proceeds from the head end of the cell toward the tail end. It is observed that the baffle 28^a is moved 20 further away from 29^a thus making the space 31^a larger than the corresponding space 31 in the ordinary agitator cells. In this way the pulp in the spitz-box is subjected to a severe hammering by the pulp circulated 25 through 31^a by the rotor and little if any froth is permitted to form. Furthermore the spitz-box is preferably divided into a plurality of spaces 16^a 16^a by provision of three vertical baffles 17^a 17^a. These baffles 30 delay passage of pulp by deflecting it back to the rotor chamber through 33^a. A cover 20^a is also provided to prevent stuff falling into the spitz-box. At the tail end of the 35 spitz-box of the mixer cell 1 there is an opening B in the end wall immediately above the floor of the cell. This opening B leads to a box E one side of which is formed by a vertically adjustable weir 40 as shown in detail in Figure 9. The height of said weir 40 is preferably adjusted by adding or removing thin slats of wood 40^a 40^a or like material, these slats fitting into grooves 40^b 40^b at each end of the slats. The level of the upper 40 edge of the weir 40 determines the level at 45 which the pulp is maintained in the preceding cell, or, more properly, determines the amount of pulp which at any moment is retained in that cell. By reason of the rapid revolution of the rotor the pulp is kept in a 50 constant state of circulation and is not permitted to settle to a definitely defined level. The pulp which overflows the weir 40 enters 55 a box F just behind the chamber E and formed between the weir 40 and the vertical back wall 80 separating the chamber F from the bearing space. The chamber F is connected by an opening C at the floor level of the elevator chamber 4 of the next cell.

Referring now to the action in the elevator chamber, shown in Figure 7 the pulp therein is dashed upward by the elevator wheel and falls forward of the partition 36 and apron 37 as indicated by the arrows 60 upon Figure 7. Falling to the bottom of 65 the space between the front wall 16 and the

partition 36, the pulp flows into the next cell through an opening D which is forward of the wall 36, and preferably near the bottom of the cell. The opening D can be at the front of the wall 36; as shown herein, said 70 opening is adjacent the bottom of the cell, but it could be raised, if desired by inserting a false bottom and bringing it to the height of the false bottom. The outlet D preferably leads into a compartment 89 75 formed by the end of the cell 15, to wall 29, the part of the spitz 16, and a vertical partition 90. The pulp gets out of this box through an extension of opening 33 and thence into the rotor or agitator chamber. This compartment is fitted with a cover 91.

It will be observed that by the construction above described the weir 40 defines the lower edge of a duct at a predetermined and adjustable level for the flow of pulp into the elevator chamber, and that the vertical wall 36 and apron 37 (Fig. 7) establish an outlet duct from the elevator chamber at the level of the upper edge of apron 37, this outlet 90 duct being at a level higher than the inlet duct in any of the positions to which weir 40 is adjustable. The weir 40 therefore regulates the pulp level in the cell preceding it. Means are thus provided for maintaining 95 any relative pulp levels in the different cells that may be desirable in the operation of the apparatus.

In cell 2 the pulp is dashed upward and forward by the rotor as explained in connection with Figure 6 of the drawing in the above description of the operation taking place in the first or mixer cell. The pulp proceeds from the head end to the tail end of the second cell, during its course 100 being repeatedly dashed upward and and through the space 31 into the spitz-box K where the concentrate froth overflows the lip 18, the body of the pulp returning through the opening 33 to be again circulated 105 through the same cycle by the rotor. The partitions 5 serve to retard the flow of pulp through the cell, the size of the opening 20 (Figure 4) being insufficient to permit such rapid flow of the pulp as would permit it to escape with insufficient agitation. At the foot of this cell the construction provided for maintaining the level of pulp by 110 an adjustable weir 40 and conducting it to the next cell is the same as described above in connection with the mixing cell.

As will be apparent from Figures 1 and 2, the boxes F and E through which the pulp flows over the weir 40 are located forward of the shaft 6 thus leaving sufficient 115 space between the successive cells at the rear of these boxes for the mounting of shaft bearings between the ends of adjoining cells. Such bearings are shown at 9 and 10 in Figure 1, and the bearing 9 is shown upon an 120

enlarged scale in Figure 2. In order to prevent the pulp from passing through the openings in the end walls of the cells through which the shaft passes we have provided deflectors and cover plates therefor, shown in detail in Figures 2, 3 and 4. In Figure 5 is shown in a detail sectional view the manner in which the deflectors and cover plates are mounted. The deflector 43 comprises a hollow cylindrical part 44 and two annular conical flanges 45 and 46 which diverge from the shaft in a direction toward the interior of the cell. The member 43 is fixed to the shaft by a set screw or otherwise, the cylindrical part 44 lying within a circular opening in the end wall of the cell, fixed to the inner face of the end wall is the cover plate 47. This cover plate comprises a flange 48 which lies against the end wall and is bolted thereto, an outwardly extending conical section 49 and a flat top 50. In operation the amount of pulp in the cell is not sufficient to cause it to pour through the opening 51 around the shaft 6, but the pulp is being constantly dashed upward by the rotor and it is necessary to provide means for preventing that part of the pulp which is dashed against the end wall and shaft from passing out through the opening 51. That part of the pulp which lodges upon the shaft 6 is arrested by the flanges 45 and 46 and caused to drop back into the cell, and the direct precipitation of pulp against the end wall around the opening 51 and against the deflector 43 is prevented by the cover plate 47. We have shown this cover plate 47 as provided with a slot 52 at the lower side to permit any pulp that is deflected by part 43 to flow back into the cell. We have also shown in Figure 2 collars 53, one of which is preferably fixed to the shaft 6 at each side of each of the bearings 9 and 10 in order to constitute a further safeguard against the entrance of pulp into the bearings.

By the means above described we provide an aligned series of practically any necessary number of flotation cells upon one level, all operated by a single shaft, and with sufficient shaft bearings to prevent whipping or objectionable vibration. The elevators pick up and move the pulp at a rate sufficient to keep the pulp level lower upon the discharge sides of the weirs 40 than upon the head sides thereof, thereby causing the pulp to flow freely from cell to cell, and by adjustment of the weirs means are provided for accurately and independently adjusting the level of pulp in each of the cells. The use of elevators of the type described makes it possible to treat comparatively coarse sand particles. Without such elevators the operation of the apparatus would be confined to finely pulverized ore that would flow naturally from cell to cell. The

elevators, besides their function of lifting the pulp and moving it from cell to cell, act as agitators and assist in the aeration of the pulp and the mixing of re-agents therewith. The possibility of maintaining the pulp level independently in the different cells renders the machine especially adaptable for taking off different concentrates in different cells. Re-agents of different kinds and in different amounts can be added in the different cells and this in connection with the possibility of independently regulating the level in the spitz-box K of each cell renders the apparatus especially adaptable for selective flotation.

While our improved apparatus can be operated without the elevators while retaining other advantages above described, such mode of operation is generally undesirable for the reason that without elevators the level of the pulp is higher at the head end of the machine than at the tail end, and this is opposed to the condition ordinarily desirable. Ordinarily froth is formed more abundantly near the head end of the machine, the pulp at this time containing all of the flotation material, whereas the more or less depleted pulp at the tail end of the machine gives rise to a less abundant froth, thereby generally rendering it desirable to maintain a higher level in the cells near the tail of the machine. Upon reference to Figure 6 it will be apparent that the area on which froth forms can be readily enlarged or restricted according to the requirements of particular ores as for instance by moving the apron 17 with its lip 18 toward the front or back of the machine to widen or narrow the area upon which froth forms or by the use of pointed choke boxes 95, 95 of the usual form, thus affording means of controlling the operation of the apparatus and the depth of the froth layer.

The complete enclosure of the apparatus by the hood 27, depending wall 28 (Figure 6) and the external walls of the cells is advantageous in that with certain flotation agents, including gases the air in the cells becomes highly charged with vaporized or gaseous re-agent. By confining this charged air to the apparatus the objectionable diffusion and loss of vaporized agent is to a great extent prevented and the re-agent-charged air is utilized for froth function. The openings 51 in the cell walls through which shaft 6 passes (Figure 5) provide sufficiently for the entrance of air to the cells, and the air so entering finds its way to the pulp through the openings 23 and 26 between the bars 22 and 25 of the agitator and elevator rotors.

In some cases we have passed the air in through a series of relatively small holes bored in the top sections of the hood 27 and a certain amount of air finds its way in

through the inlet space formed by 90. When desired air can be admitted under slight pressure.

We claim as our invention:

- 5 1. A flotation apparatus comprising an aligned series of cells, each consisting of an impeller chamber, and an elevator chamber communicating with the head end of said impeller chamber at its bottom, a 10 shaft extending lengthwise of said cells, impellers and elevators mounted on said shaft and within said impeller and elevator chambers respectively, and discharge ducts connecting the tail end of each impeller chamber with the following elevator chamber, and means for maintaining the pulp level at the intake to each elevator chamber substantially lower than at the discharge therefrom.
- 15 2. A flotation apparatus comprising an aligned series of impeller chambers disposed on the same level, elevator chambers intermediate said impeller chambers, an elevator in each elevator chamber, discharge ducts 20 connecting each impeller chamber with the following elevator chamber, and a weir in said ducts for maintaining a relatively higher pulp level in each preceding impeller chamber than in the following elevator 25 chamber.
3. In a flotation apparatus, a flotation cell, a horizontal shaft extending through said cell, a partition extending across said cell transversely of said shaft, said partition being provided with an opening to receive said 30 shaft and forming impeller and elevator chambers in said cell, a cylindrical impeller and a cylindrical elevator mounted on said shaft in said impeller and elevator chambers respectively, a spitz box communicating with said impeller chamber and also said elevator chamber communicating with said impeller chamber through a duct having a relatively high level and thence through an 40 opening adjacent the bottom of said partition.
4. In a flotation apparatus, a flotation cell, a horizontal shaft extending through said cell, a partition extending across said cell transversely of said shaft, said partition being provided with an opening to receive said shaft in said impeller and elevator chambers in said cell, a cylindrical impeller and a cylindrical elevator mounted on said 45 shaft in said impeller and elevator chambers respectively, a spitz box communicating with said impeller chamber at two different levels and also communicating with said elevator chamber through a duct at a 50 level higher than said spitz box.
5. A flotation apparatus comprising an aligned series of alternating impeller and elevator chambers disposed upon the same level, a shaft extending through said series of chambers, impeller and elevator means actuated by said shaft in said impeller and elevator chambers respectively, spitz boxes communicating with said impeller chambers, a duct communicating from a relatively high level in each of said elevator chambers to the succeeding impeller chambers and a duct 65 communicating from each of said impeller chambers to the succeeding elevator chambers having means therein for controlling a normal level of ore pulp in its respective impeller chambers and spitz box.
6. A flotation apparatus comprising an aligned series of alternating impeller and elevator chambers disposed upon the same level, a shaft extending through said series of chambers, rotary impeller and elevator means actuated by said shaft in said impeller and elevator chambers respectively, spitz boxes offset forwardly of said shaft on one side of said impeller chambers and communicating therewith, a relatively high partition in each of said elevator chambers offset forwardly of its respective elevator, and forming a passage having communication with the succeeding impeller chamber, and a duct 80 communicating from each of said impeller chambers to the succeeding elevator chambers having means therein for controlling the normal level of ore pulp in its respective impeller chamber and spitz box.
7. A flotation apparatus comprising an aligned series of cells disposed upon the same level and adapted to contain an ore pulp, bearing spaces between some of said cells, a shaft extending through openings in said 85 series of cells, bearings for said shaft in said bearing spaces, means permitting passage of air in and out of said cells, adjacent said shaft opening but excluding ore pulp from said bearing spaces and means driven by 90 said shaft for agitating said pulp and for moving the same from cell to cell.
8. A flotation apparatus comprising an aligned series of alternating impeller and elevator chambers disposed upon the same level, a shaft extending through said series of chambers, impelling and elevating means actuated by said shaft in said impeller and elevator chambers respectively and a duct 100 connecting successive impeller and elevator chambers having an adjustable weir therein for controlling the level in the preceding impeller chamber.

Signed at Wallace this 25th day of June, 1924.

TOM M. OWEN.
MICHAEL P. DALTON.
